UNITED STATES PATENT OFFICE

SYLVESTER H. HUNT, OF NORFOLK, VIRGINIA

STAPLING MACHINE

Application filed May 28, 1931. Serial No. 540,723.

The object of this invention is to provide a fluid pressure (preferably air) mechanism for imparting to the stapler bar its actuating stroke, the advantages of using an expansible fluid for performing this operation being to enable the stitches or stapling operations to be made quicker and with less effort on the part of the operator and also to enable the power of the stapling stroke to be readily regulated, as more fully hereinafter set forth.

In the drawing annexed:

Fig. 1 is a vertical sectional view of a well known form of stapling machine having my invention applied thereto; and

20 Referring to the drawing annexed by reference characters, 5 designates the usual hollow vertical pedestal of the machine in which reciprocates a vertical piston rod 6 having attached to its upper end a lateral arm 7 carrying the usual vertical stapler or stitching rod 8.

25 The lower end of the piston rod 6 has attached to it a solid piston 9 working in a cylinder 10 mounted rigidly within the pedestal, its lower end being open and its upper end being closed. Entering the cylinder, at a point above the piston is a port to which is connected 30 a pipe 11 which passes through a hole in the pedestal and is connected at its outer end to a tubular valve cylinder 12. In this tubular valve cylinder is arranged a double piston valve 13 which is normally pressed 35 into inoperative position by means of a spiral expansive spring 14 arranged between one of the pistons of the valve and the adjacent head of the cylinder 12. Connected to the cylinder 12 at a point between the two valve pistons 40 is an inlet pipe 15 which is intended to be connected to any source of expansible fluid under pressure, air being the most desirable fluid. Extending out through the other head of the valve cylinder 12 is a rod 45 16 which is connected to an operating pedal 17. With this construction it will be observed that when the double piston valve is at its lower point, where it is kept normally by the spring 14, no air can enter the cylinder 10, but when the double piston is actuated by 50

the pedal, against the action spring 14, the air from pipe 15 will have free access to the cylinder 10 and will thus force down the piston 9 and cause an operation of the stapling rod to take place. When the operator removes his foot from the pedal the spring 14 expands and thus closes the valve, shutting off the supply of compressed air and putting pipe 11 into communication with the atmosphere through a port or ports 18 formed in the valve cylinder 12.

When the pressure in the cylinder 10 is thus relieved the piston rod and stapler rod will be quickly elevated into inoperative position by means of an expansible coil spring 19 housed in the pedestal 5 and having its lower end seated against an abutment 20 on the interior of the pedestal and its upper end against an abutment 21 carried by the piston rod.

With my apparatus it will be seen that the working stroke is formed entirely by an expansive fluid and that therefore by varying the pressure of the fluid I may readily vary the power of the stroke to suit the conditions and nature of the work in hand. This fluid mechanism also enables the working stroke to be made quicker and further there is a desirable resilience in the work of cutting and shaping and driving the staple. Also the effort on the part of the operator is reduced to a minimum, his effort being confined entirely to the pressing of a small light spring 14. It will be observed further that my mechanism lends itself nicely to compactness, which is desirable not only for shipping purposes but for the saving of space in the shop, this compactness being due to the fact that both the operating cylinder and the lifting spring are mounted in the usual hollow pedestal of the machine.

The upper closed end of the cylinder 10 is rigidly but removably fastened within the pedestal by means of a plurality of machine bolts 22 which pass through holes formed in the pedestal wall and tapped into the head of the cylinder, the outer wall of the head of the cylinder being tapered to fit solidly against the inner face of the wall of the pedestal. To increase the solidarity of this anchorage 100

in the pedestal I prefer pouring into the annular space between the cylinder and the pedestal a Babbitt metal filling 23 which adheres to the cylinder and to the pedestal wall and thus assists materially in centering the cylinder within the pedestal. I prefer providing the head of the cylinder with a separable head 24 which is screwed down into the cylinder and carries a piston-packing 25. To keep this packing 25 tight I tap into the underside of the head 24 a gland 26, and I utilize this gland 26 as a stop for limiting the upward movement of the piston 9 under the influence of the return spring 19. This arrangement is desirable because by housing the cylinder within the pedestal it would be impossible to get at the gland 26 for adjustment purposes without removing the cylinder from the pedestal or making a hole in the pedestal, whereas with my arrangement I can readily get access to the gland 26 and also to the rings of the piston by simply disconnecting the fastening nut of the piston and slipping the piston downwardly out of the cylinder.

In accordance with the provisions of the patent statutes, I have herein described the principle of operation of my invention, together with the apparatus which I now consider to represent the best embodiments thereof, but I desire to have it understood that the apparatus disclosed is only illustrative and that the invention can be carried out by other means. Also, while it is designed to use the various features and elements in the combinations and relations described, some of these may be altered and others omitted and some of the features of each modification may be embodied in the others without interfering with the more general results out-

lined, and the invention extends to such use.

I claim:

1. In a stapling machine embodying a hollow pedestal, a vertical piston rod for operating the stapler, a piston on the lower end of said rod, a cylinder for this piston, and valve means for admitting and exhausting an expansive fluid into and out of the cylinder at a point above the piston to thereby perform the working stroke under the action of an expansive fluid, and spring means for returning the rod of the stapler preparatory to another working stroke, said cylinder being housed and centered within said hollow pedestal at the lower end thereof and having its top closed and its bottom open.

2. In a stapling machine, a hollow pedestal, a piston rod extending up through said hollow pedestal and having connected to its upper end the stapling device operable upon the down stroke of said piston rod, a return spring housed within said pedestal, an actuating cylinder housed within the pedestal at a point below the spring and rigidly but removably fastened to the inner face of the wall of the pedestal, a piston attached to said piston rod and working in said cylinder, said cylinder having an open lower end and a closed upper end, the closed upper end being provided with a removable packing-carrying member and also an adjustable gland for said packing, this gland being arranged in the upward path of the piston so as to serve as a stop for the upward, return stroke thereof.

In testimony whereof I hereunto affix my signature.

SYLVESTER H. HUNT.
